UNITED STATES PATENT OFFICE.

ASA W. FARNEY, OF KANSAS CITY, AND FRANK W. JANSKY, OF ST. JOSEPH, MISSOURI.

RIPRAP.

1,252,678.

Specification of Letters Patent. Patented Jan. 8, 1918.

Application filed August 2, 1916. Serial No. 112,851.

To all whom it may concern:

Be it known that we, ASA W. FARNEY and FRANK W. JANSKY, citizens of the United States, residing, respectively, at Kansas City, in the county of Jackson, and St. Joseph, Buchanan county, State of Missouri, have invented certain new and useful Improvements in Ripraps, of which the following is a specification:

10 This invention relates to ripraps for preventing a rapidly flowing stream from cutting away its banks and causing the streams to rebuild or refill cuts in their banks, and the object is to produce a riprap of simple, 15 strong, durable and comparatively inexpensive construction, which can be laid with facility, and be easily and firmly anchored, and which performs its protecting function efficiently and without the tendency to produce 20 cave-ins frequently incidental to the use of stone ripraps, or ripraps which must be heavily weighted with broken stone to retain them in position.

A further object is to produce a metallic 25 riprap, which tends to grip the bed of a river or stream, and possesses in a high degree the property of resistance to corrosive action when submerged in water, and which can be transported in folded condition to, or 30 the part of which can be assembled at the point where it is to be laid, with ease and despatch and at comparatively low cost.

With these objects in view the invention consists in certain novel and peculiar features of construction and combination of parts as hereinafter described and claimed; and in order that it may be fully understood reference is to be had to the accompanying drawing, in which—

40 Figure 1, is a plan view showing a section of riprap embodying the invention, applied in operative position to a point on the bank of a river where such bank is being cut away by the water.

45 Fig. 2, is a transverse section showing how the plates will adapt themselves to the surface configuration of the bed of the river or stream so that each plate shall rest flatly thereagainst.

50 Fig. 3, is an enlarged cross section through one of the plates of the riprap and also shows said plate threaded on crossed anchoring wires or cables.

Fig. 4, is a perspective view of one of the plates. 55

Fig. 5, is a plan view of a modified form of construction of the riprap.

Before proceeding with a detailed description of the invention, it is desirable to state that many attempts have been made 60 to produce efficient riprap as a substitute for the ripraps commonly made of woven willow branches and weighted with broken stone. Ripraps made of heavy slabs of concrete wired together have been made but 65 these have proven impracticable due to the fact that the weight of the slabs would result in rupturing the anchoring cables and also because they would impose such weight upon the bed or bank of the stream that 70 cave-ins would ensue.

We propose to overcome this difficulty by providing a flexible bed composed of cast iron plates, as such plates have been found to possess great corrosion-resisting properties when completely submerged in water, and to secure these plates together by cables or wires protected from corrosion by galvanizing or otherwise. It has been found that a riprap composed of thin flat plates of the 80 character mentioned properly anchored avoids the objections above mentioned as incidental to the use of concrete slabs, and possesses the additional advantage of being easily, quickly and cheaply laid without the 85 danger of rupturing the anchoring cables when the riprap is being paid off into the water, this being one of the difficulties which has been encountered in the laying of concrete-slab ripraps. 90

By the use of these plates the anchoring cables are not subjected to any material stress and hence the riprap can be rapidly laid without danger of the loss of any section of it through the breaking of cables. 95

Referring now to the drawing in detail, 1 indicates thin cast metal plates provided near opposite sides with a set of openings 2, and near the other or remaining sides with a set of openings 3.

In the preferred construction, the plates will be provided with upwardly bowed portions 4, of conical form in plan view, and the openings 2 and 3 will be formed in the apices of the respective bowed portions, so that 105 longitudinally extending anchoring wires or

cables 5 and transversely extending anchoring wires or cables 6, may be threaded through the alined openings 2 and 3 respectively, without being bent or kinked, as appears clearly in Fig. 3.

The down-stream ends of the wires or cables 5 will be enlarged in any suitable manner, as by knotting as at 7, and the up-stream ends of said wires or cables will lead 10 up over the adjacent bank and be secured to dead-men 8. The inner ends of the transverse cables 6 will be likewise enlarged as at 7, and their outer ends will lead up over the bank and be secured to dead-men 9, it being 15 preferred that a plurality of adjacent transverse cables will be anchored to a single dead-man as there will not be as much strain upon the dead-men 9, while the riprap is being laid, as upon the dead-men 8. After 20 the cut-away portion of the bank has been filled through deposits therein of sand and the like by the stream, there will be practically no strain tending to slide the riprap out into the stream. It will be further noted 25 that the flat plates will have a frictional grip upon the bed of the river or stream because they will be sufficiently heavy for said bed to enter the recesses formed in the undersides of the plates through the up- 30 wardly bowed portions thereof. The entrance of the bed into these recesses will not only tend to guard against endwise or side- 35 wise movements but will tend to guard against twisting or turning movements of the plates on the bed.

In Fig. 5, the plates are pivotally inked together by rings 10 instead of being threaded upon wires or cables. In this case the up-stream series of plates will be anchored by 40 suitable cables 11 to the dead-men 8, and the outer series of longitudinally alined plates will be anchored by cables 12 to dead-men 9.

A riprap composed of thin metal plates flexibly connected together either by continuous wires or cables or by links 10 can be conveniently folded or rolled for transportation and as conveniently laid from a scow or float. For convenience of illustration the ends of the caved-in portion of the 45 bank are squared in a manner which would not result from natural action of the water. It is so illustrated for convenience in showing the end plates of the riprap at an angle, and in practice it is desirable to cut the bank 50

in substantially this manner preliminary to 55 the laying of the riprap so that the bank on which the plates of the up and down-stream ends initially rest shall be fairly uniform and therefore initially give a firm and stable plate rest or support for the said riprap. It 60 will be understood that it is not necessary to so cut the banks at the ends of the cut-away portion. If the upstream bank for example, follows the direction indicated by the dotted line 18, the plates above said line may rest 65 upon the top of the bank or may be dispensed with.

From the above description it will be apparent that we have produced a riprap possessing the features of advantage enumerated as desirable and we wish it to be understood that while we have illustrated and described the preferred construction of the same we reserve the right to make all changes falling within the spirit and scope 75 of the appended claims.

We claim:

1. A riprap comprising a set of thin plates arranged side by side in longitudinal and transverse rows, each plate being bowed upward at each edge to provide recesses, and each bowed portion being provided at its inner end with an opening, the opening at each side being alined with the opening at the opposite side, flexible cables paralleling the longitudinal rows and extending through the longitudinally alined openings of such rows, transverse cables paralleling the transverse rows and extending through the other openings of said plates, anchors 80 for the corresponding ends of the longitudinally extending cables, and anchors for the corresponding ends of the transversely extending cables.

2. A thin metal plate of substantially rectangular form, provided midway the length of each edge with an upwardly bowed conical portion to form a downwardly facing recess, and provided at the apex of each conical portion with an opening in the plane of 85 the upper side of the body of the plate.

In testimony whereof, we affix our signatures, in the presence of two witnesses.

ASA W. FARNEY.
FRANK W. JANSKY
